UNITED STATES PATENT OFFICE

157,600

ROOM THERMOSTAT

Roy W. Johnson and Vernon R. Pawelsky, Milwaukee, Wis., assignors to Automatic Products Company, Milwaukee, Wis., a corporation of Wisconsin

Application February 4, 1948, Serial No. 144,253

Term of patent 14 years

(Cl. D52—7)

To all whom it may concern:

Be it known that we, Roy W. Johnson and Vernon R. Pawelsky, citizens of the United States, residing at Milwaukee, in the county of Milwaukee and State of Wisconsin, have invented a new, original, and ornamental Design for a Room Thermostat, of which the following is a specification, reference being had to the accompanying drawing, forming a part thereof, and in which:

Figure 1 is a front elevational view of a room thermostat, showing our new design;

Figure 2 is a side elevational view thereof;

Figure 3 is a top plan view; and

Figure 4 is a bottom plan view.

Our design is characterized by the provision of an opening in the top wall of the casing through which the indicator dial projects and which opening interrupts an upstanding rib on the casing wall so that portions of said rib forwardly and rearwardly of the opening lie imme-

dately adjacent to the indicator dial, with the forward portion of said rib tapered and terminating between two quadrant-shaped openings.

We claim:

The ornamental design for a room thermostat, as shown and described.

ROY W. JOHNSON.

VERNON R. PAWELSKY.
